JOHN W. RUSSELL AND DAVID JOLINE, OF TOTTENVILLE, NEW YORK.

Letters Patent No. 73,758, dated January 28, 1868.

IMPROVEMENT IN ANCHORS.

The Schedule referred to in these Letters Patent and making part of the same.

TO ALL WHOM IT MAY CONCERN:

Be it known that we, JOHN W. RUSSELL and DAVID JOLINE, of Tottenville, county of Richmond, and State of New York, have invented a new and useful Improvement in Anchors; and we do hereby declare that the following is a full, clear, and exact description of the construction and operation of the same, reference being had to the accompanying drawings, making a part of this specification.

The nature of our invention consists in the combination of double and pivoted flukes with the double shanks of an anchor, when constructed in the form of a bow to an ox-yoke, or the breast-bone of a turkey, or the letter U, so that, while two palms of the flukes may be in the ground, to take the strain, the other two palms of the flukes will be closed down on the shanks, and the fouling of the chain or cable of a vessel will thereby be prevented.

We construct the shanks of the anchor in the form above referred to, with a fluke on each end of the shank, and attach the cable or chain to the centre of the shank. The flukes are attached by bolts to the shank, being made to swivel thereon as in the anchor known as the Porter's patent or swivel-fluke anchors. In the accompanying drawings—

Figure 1 represents a perspective view of the anchor in its proper position, with its two flukes buried in the ground.

Figure 2 shows the form of the shanks, and the flukes are secured to the ends *b b*.

The flukes, with their palms, are shown at *c*, in Figure 3.

The attachment of the cable or chain is shown at *a*, in fig. 2.

The distance of the ends of the shank should be sufficient to cause one palm of each shank to fall upon the ground or bottom without the aid of an anchor-stock.

In this our improved anchor it will be observed that the difficulty of fouling the chain with the anchor, as we construct it, is in great measure thus obviated, and this we hold an important feature of our improvement.

Having thus fully described our invention, what we claim therein as new, and desire to secure by Letters Patent, is—

The combination of the double and pivoted flukes with the double shanks of the anchor, when constructed substantially in the manner and for the purpose as herein described and shown.

JOHN W. RUSSELL,
DAVID JOLINE.
